UNITED STATES PATENT OFFICE.

THOMAS M. RIGGLE, OF OAKLAND, CALIFORNIA, ASSIGNOR TO RIGGLE AUTOMATIC TRAIN CONTROL COMPANY, OF OAKLAND, CALIFORNIA, A CORPORATION OF CALIFORNIA.

AUTOMATIC TRAIN CONTROL.

Application filed April 29, 1924. Serial No. 709,779.

My invention relates to means for limiting the speed of a train and for automatically stopping the train or decreasing the speed thereof when a block section of track preceding the train is not in normal condition.

An object of the invention is to provide an extremely simple and positively acting electrically and magnetically operated mechanism which will cause the application of the train brakes when a block section of the track preceding the train is not in normal condition and the train speed exceeds a predetermined value.

Another object of the invention is to provide means of the character described which will cause the application of the brakes when the train exceeds a predetermined speed regardless of the condition of the track preceding the train.

A further object of the invention is to provide means which will temporarily render the automatic brake applying mechanism inoperative providing the speed of the train is not in excess of a predetermined value.

A still further object of the invention is to provide a single means associated with the track for causing the operation of the apparatus to effect the foregoing objects.

The invention possesses other objects and features of advantage, some of which, with the foregoing, will be set forth in the following description of the preferred form of my invention which is illustrated in the drawings accompanying and forming part of the specification. It is to be understood that I do not limit myself to the showing made by the said drawings and description, as I may adopt variations of the preferred form within the scope of my invention as set forth in the claims.

Referring to said drawings:

Figure 1 is a view, mainly diagrammatic, of the mechanism of my invention shown in connection with a locomotive and a track section.

Figures 2 and 3 are respectively plan and side views of the portion of mechanism associated with each track section.

Figure 4 is an enlarged detail sectional view taken on the line 4-4 in Figure 2.

Figure 5 is a diagrammatic plan view showing the relative positioning of cooperat-

ing train and track elements of the device.

In Figure 1 of the drawings the portion shown above the track 2 is arranged to be carried on the train, while the portion included between the rails of the track is adapted to be held in substantially fixed association with respect to the track. As here illustrated, the track comprises rails 3 and 4 and is divided into insulated block sections as in signal control systems, three of such sections 6, 7 and 8 being here represented. In the present embodiment, my invention is used in connection with the air-brake-system of the train, and accordingly a well known type of this system is here diagrammatically illustrated and shown above the representation of the track. Included in the brake system is the engineer's brake-valve 9 connected to the air reservoir 12 by reservoir pipe 13, and connected to the brake-pipe 14 by the branch 15. As is usual the brake-pipe communicates with the distributing valve and triple valves on the cars of the train, the valves being caused to bring about the application of the brakes when the pressure in the brake-pipe decreases below a predetermined point.

The brake-valve is provided with a suitable control lever 17 adapted to be placed in various positions, such as release, running and service, the latter causing a reduction of the pressure in the brake-pipe and consequent application of the brakes. In the present arrangement the mechanism of my invention operates in conjunction with the control lever of the brake-valve, and suitable mechanical actuating means are therefore associated with said lever and adapted to be operated by my automatic control means. The lever actuating means includes a cylinder 18 which is fixed positioned adjacent the brake-valve and in which a piston 19 is mounted for reciprocation. The latter is provided with a rod 21 which extends through the cylinder head 22 and is adapted to releasably engage the lever so as to move it to service position.

Formed in the cylinder so as to lie on opposite sides of the piston in all of the positions thereof are ports 23 and 24 which by means of the pipes 26 and 27 afford the cylinder communication with the reservoir and brake-pipe respectively. The pipe 26 includes a feed valve 28 which normally

maintains sufficient pressure in the portion of the cylinder 29 associated with port 23 to exceed the pressure obtaining in the brake-pipe. In this manner, under normal conditions, the piston-rod will be held entirely released from the control lever, and the latter may be manipulated at will. However, should the pressure in the chamber 29 be reduced below the brake-pipe pressure, 10 the piston rod will be moved to place the lever in service position and an application of the brakes will result.

Accordingly, therefore, means are provided for automatically causing a reduction 15 of the pressure in the chamber 29 when a train travelling in excess of a predetermined comparatively slow speed approaches a track section which is not in normal condition. As here shown, said means comprises 20 a pipe 31 which communicates at one end with the chamber 29 and at the other end with an electro-magnetically operated application valve 32. The latter includes a valve stem 33 in the form of a magnetic core 25 which is associated with a magnet coil 34 and is arranged to control the flow of air through the valve. When the coil is energized the core closes the valve passage 35; however, when no current flows through the 30 coil the core may be displaced by the pressure of air in pipe 31 and thereby permit the air to escape through outlet 36 and thus relieve the pressure in chamber 29. The coil 34 is arranged in a normally closed circuit 35 37 containing a suitable source of current such as the battery 37'. Associated with the circuit 37 and arranged in parallel with each other and the coil 34 is a plurality of longitudinally, aligned magnetically operated 40 gravity switches 39 contained in short-circuiting branches 41 offering low electrical resistance as compared with the coil 34. Each of the switches includes an armature 43 which is normally held raised from engagement 45 with a cooperating contact member 44 forming part of the circuit 37 by means of the attraction of a relatively weak bar magnet 46 which is strong enough to hold the armature, but not strong enough to raise it 50 from its lower position. It will now be understood that if either or both armatures are caused to engage contact member 44, the current will be diverted from the coil 34 through a branch circuit 41 and back to 55 battery 37' with the result that the core 33 will become demagnetized, and the pressure in the chamber 29 may be relieved to bring about an application of the brakes. It will now be noted that with switches 39 all open, 60 the current from battery 37' will pass through conductor 37^a, will be divided between the contact member 44 and a similar member hereinafter more particularly referred to and which is connected in parallel 65 with the member 44, and will then pass

through conductor 37^b, coil 34, and back to battery through conductor 37^c. On the other hand, when one or more of the switches 39 is closed, the major portion of the current from battery 37' will pass through conductor 37^a to contact member 44, through the member 44 to the closed switch or switches 39, through the branches 41, and thence back to battery through conductor 37^c, thus so weakening the current through the coil 34 that the valve 32 will be permitted to open. Means are provided for causing the armature 43 to be moved into contact with the member 44 against the resistance of the magnets 46, when the track section preceding the train is not in normal condition, such means being inoperatively disposed with respect to the switches 39 when track conditions are normal. As here shown, said means comprises a relatively strong magnet 47 associated with each track section and arranged to be moved transversely from one position to another so that when the train passes thereover the armatures 43 will or will not be affected thereby in accordance with the condition of the preceding track section. Each of the track magnets, as here illustrated, is of the permanent horseshoe type and is mounted on a carriage 48 arranged on an inclined runway 49. The carriage is preferably arranged between and is adapted to move transversely of the track rails. The switches 39 are so positioned on the train that when the train passes by the track magnet while the carriage is at the higher end of the inclined runway, the switch magnets 46 and associated armatures 43 will pass transversely of the magnet 47 at such distance as not to be appreciably affected thereby, whereas, with the magnet carriage positioned at the lower end of the runway, one pole of the switch magnet 46 will pass over in close proximity to a track magnet pole of like polarity. In the latter event, it will be evident that while the magnet poles are passing, the attraction of the switch magnets 46 for the armatures 43 will be neutralized and the armatures will be moved by gravity and the excess attraction of the track magnet to engage the contact member 44, thereby effecting the setting of the brakes in the manner previously described.

The proper positioning of the track magnet in accordance with track conditions is here shown effected through the agency of a motor 51 and an electro-magnetic clutch 52 mounted upon a shaft 53 driven through a worm 54 and wheel 55 by the motor. Carried on said shaft for relative rotative movement thereon is a sleeve 57 which is fixed to a drum 58 about which is adapted to be wound and unwound a cable 59 attached to the track magnet. Connection between the shaft and sleeve is effected by means of the clutch, the winding 61 thereof being ar-

ranged on the sleeve while the magnetic plate or armature 62 carries the wheel 55. The motor and clutch are connected in series in a circuit 63 having a suitable source of current such as the battery 64 and provided with a switch 66 which is normally retained in closed position by means of the track relay 67. A suitable resistance 68 is also arranged in circuit 63 so that under normal conditions 10 the current will be merely sufficient to hold the clutch engaged but not enough to rotate the motor shaft. The sleeve and drum are held in such relation to the motor shaft, that with the track clear and the circuit 63 closed, the carriage and magnet will be held 15 at the top end of the incline as shown in Figures 3 and 4, and the switch armatures will be unaffected by the track magnet. Should the circuit 63 become broken, the 20 clutch 52 will be immediately disengaged and the carriage, due to gravitational force, will move down the incline and the magnet will be in position to influence the armatures 48. Fixed for rotation in synchronism with 25 the sleeve is a segmental circuit breaker 69 which is connected in parallel with the resistance 68. As shown in Figure 4, the circuit breaker comprises a broken conductor ring 70^a carried on the sleeve 57 and insulated therefrom, brushes 70^b being utilized to provide the necessary contact therewith. When the magnet is inoperatively disposed, the circuit breaker is likewise positioned; however, when the magnet is in operative 35 position the circuit breaker completes a shunt around the resistance. In this manner as soon as the track returns to normal condition and the circuit 63 again becomes closed, practically the full line current will 40 pass through the motor and the shaft of the latter will be rotated. Rotation of the motor shaft will continue until the track magnet has been moved to its inoperative position, at which time, as above explained, the circuit breaker will open the shunt and the magnet will be thus left in said latter position.

It will now be noted that the rails 3 and 4 of each track section or block form part of 50 a constantly closed track circuit containing a track relay 67 and a battery 10, and that the relay 67 of each section circuit is arranged to operate the switch 66 of a section behind it. Thus, as herein particularly 55 shown, the track magnet and mechanism positioned in the track section 7 is particularly arranged to be controlled from the track section 8, it being noted that when a train is positioned in the section 8, circuits 60 will be provided through its sets of wheels and axles to electrically connect the rails and thereby short out the portion of the track circuit containing the relay 67 to allow the opening of the switch 66. In this manner, 65 the switch 66 will be caused to remain open

until the train leaves the block 8 so that any train attempting to enter the block 7 while a train is in block 8 will have its brakes automatically set in the manner hereinbefore described. It will now be noted that 70 when the train leaves block 8, the normal current flow through the track relay 67 will be resumed to thereby close the corresponding switch 66 and cause the track magnet to be drawn back to its normal position at the 75 top of the incline. While I have herein shown the device of my invention applied to a one-way track to provide control of a following train for only one block behind a leading train, it will be obvious that control 80 for a two-way track or for more than one track magnet behind a train merely requires the duplication of the magnet positioning mechanism and an appropriate system of interconnected track relays similar to those now used in block signal systems. It will also be noted that the various mechanisms of the device are illustrated throughout as in the condition of normal running of a train with the track sections in proceed condition, 85 the different control positions being described in detail herein in connection with the description of the various operations of the device.

In the event that the automatic control mechanism on the train in passing over the track magnet, operates to cause the setting of the brakes, the latter may only be released upon the engineer raising the armatures 48 by hand, whereupon the valve 33 is 90 reseated, the pressure in pressure chamber 29 builds up again and the piston rod is withdrawn from operative engagement with the control lever of the brake valve to allow the engineer to release the brakes. 95

Means are provided for temporarily rendering the automatic-brake-applying mechanism inoperative providing the speed of the train is not in excess of a predetermined value. Fed with air from the main reservoir 13 through a restricted-port-valve 70, is a volume tank 71 which is adapted to contain a comparatively limited amount of air under pressure. The volume tank is in turn connected with an electro-magnetically operated pressure valve 72 which is provided with a stem 73 arranged to be actuated by the magnet core 74. The valve is provided with a passage 75 which is normally 100 kept shut by means of a spring pressed valve element 76. Opening of the passage 75 is effected by energizing the magnet coil 77 in which the core 74 is arranged, the coil being contained in an electric circuit 78 which includes a suitable source of current such as a battery 78'. The passage 75 is connected with a piston valve 79 into which the air from the passage is arranged to discharge when the valve element 76 is open. The piston valve includes a piston 80 to 105 110 115 120 125 130

which is fixed a rod 81 having preferably secured thereto a contact 82 which is adapted upon the displacement of the piston 80 to bridge a pair of spaced contact elements 83 arranged in an electric circuit 84 having a suitable source of current such as the batteries 84' included therein. Contained in the circuit 78 and positioned to lie at the front and rear of the switches 39 are gravity switches 86 of the same type as are the switches 39, each of which in the present embodiment of the invention comprises a bar 87 which is normally magnetized but possesses insufficient magnetic strength to draw a pivotally mounted armature 88 thereto and thereby complete the circuit 78 through the armature and a contact 89. The switches 86 are thus also arranged to pass over a pole of the track magnet when the carriage of the latter is in operative position, or in other words, when the track section ahead of the train is not clear. The poles of the bar magnet 87 and track magnet 47 which are arranged to operate are of unlike polarity, so that as the weaker magnet 87 passes over the relatively strong pole of the track magnet, an increased magnetic strength will be induced in the magnet 87 and the armature 88 will be drawn upward thereby to close the circuit 78. It will be noted that the pivoted switch armature 88 is arranged to normally lie in a support 90 and is held close enough to the contact 89 thereby as to insure its raising as the track magnet passes thereunder. The closing of circuit 78 being thus effected by the drawing of the armature 88 against the contact 89 will now cause the opening of the valve 72, so that the contact 82 will be moved against the contact elements 83 to close the circuit 84 in the previously described manner. The circuit 84, it will now be noted, also has electro-magnet coils 85 included therein, each of said coils being preferably arranged to encircle the bar magnet 46 of a switch 39 and being capable, when excited, of increasing the pull of the magnets 46 to prevent the engagement of armatures 43 with members 44 against the pull of the track magnet. The circuit 84 also provides a branch circuit around the coils 85, and which circuit is arranged to simultaneously energize coils similar to the coils 85 for a purpose to be hereinafter more fully described. Assuming, then, that the track is not clear and that the train has passed over the track magnet to close the switch 86, current will flow through coil 77 and air will be forced into the piston valve 79 to effect the closing of circuit 84, thus preventing the automatic application of the brakes. It will be noted by referring to Figure 1 that the valve 79 is provided with a relief port 91 which is adapted to

be uncovered by the piston on its forward stroke; by varying the position and size of said port the duration and time of closing and opening of the circuit 84 may be readily predetermined. Furthermore, the relative positioning of the switches 86 and 39 must be such that when the train is traveling at a speed not greater than the permissive speed, the coils 85 will have been energized by the time the switches 39 pass over the track magnet to thus prevent the application of the brakes in the manner indicated; whereas, if the train is moving at a greater than permissive speed, the brakes will be automatically set. In this manner, a train may be allowed to proceed into an adverse block, but only when going slowly enough to permit its stopping within a short distance, the mechanism thus providing what may be conveniently termed a caution-speed control.

With the circuit 78 closed at the switch 86, the current from battery 78' will flow through conductor 78^a to and through the switch 86, thence through conductor 78^b to and through the operating coil 77 of the valve 72, and thence back to battery 78' through conductor 78^c. When circuit 84 is closed between contacts 83, its current will flow from the battery 84' through conductor 84^a to a contact 83, thence through the bridge contact 82 to the other contact 83, thence through a conductor 84^b to the coils 85 which are here shown connected in series, and thence back to battery 84' through conductor 84^c. It will now be noted that as soon as a magnet 86 has passed over the track magnet, the armature thereof will drop to thereby break the circuit 78 at contact 86, and thus allow the closing of valve 72, whereupon the piston 80 will fall by gravity as the imprisoned air escapes from thereunder and the bridge contact 82 will be drawn away from the contacts 83 to break the circuit 84.

Means are also provided in connection with the mechanism just described for insuring an application of the brakes in case said mechanism fails to properly function or release, as for example, if the circuit 84 should not become broken within a reasonable period after the switches 39 pass over the track magnet. As here illustrated, said means comprises a differential-piston-valve 92 providing a cylinder 93 having bore portions of different diameters at opposite ends thereof. The bore portion of smaller diameter is connected to the pipe 31, while that with the larger diameter is connected to the volume tank 71. Mounted in the smaller and larger cylinder bore portions respectively are pistons 94 and 95, such pistons being fixed together in spaced relation whereby they may be simultaneously disposed in corresponding parts of their bores. Normally,

as indicated in Figure 1, the pistons lie at opposite sides of a relief port 97 formed in the cylinder with the piston 95 disposed at the inner end of its stroke and the piston 94 disposed at the outer end of its stroke; however, should either of the armatures 88 fail to become disengaged from the magnets 87 and thereby leave the circuit 84 indefinitely closed, the pistons 94 and 95, by reason of the continued discharge of air from the port 91 of the valve 79 and consequent reduction of pressure in the volume tank, will be displaced toward the other ends of their strokes whereby the port 97 will be placed in communication with the cylinder at the outer side of the piston 94 and the pressure in the chamber 29 will be relieved through port 97 to effect the automatic application of the brakes.

Means are also included for causing the automatic application of the brakes when the track section preceding the train is clear but the train exceeds a predetermined maximum speed. As here shown, said means are adapted to be actuated by means associated with the track, and, in fact, are arranged to be actuated by the same track magnet 47 which operates the train brakes when the track is not clear. Connected in the circuit 84 in parallel with the switches 39 therein and operable similarly thereto is a plurality of switches 101, while switches 102, adapted to operate similarly to the switches 86, are arranged in parallel with the latter in the circuit 78. Switches 101 and 102, it will be noted, are arranged in alignment longitudinally of the train with the former between the latter and are so positioned transversely of the switches 39 and 86 that they may be affected by the track magnet only when the latter is positioned in the upper or clear position. The switches 101 and 102, it will be noted, respectively include bar magnets 103 and 104 and pivoted armatures 106 and 107, the armatures 106 being arranged to contact, when displaced downwardly, with a common contact member 108 connected in the circuit of battery 37' in parallel with the contact 44, while the armatures 107 are arranged to contact with switch contacts 102 when moved upwardly, the armatures thus being similarly operable to those of the switches 39 and 86 respectively. Coils 109 are mounted on magnets 103, such coils being similar to and connected in parallel with the coils 85.

By reference to Figure 5, it will be noted that with the track magnet 47 in its lower, or adverse, position, as shown in dotted lines, one pole 111 thereof is arranged to lie in a common vertical plane with the switches 39 and 86, while the other pole 112 of the magnet will lie in a common vertical plane with the switches 101 and 102. It will now be further noted that with the magnet pole 111

having a given polarity, the lower poles of the magnets 46 of the switches 39 must have a like polarity thereto, while the lower poles of the magnets 87 of the switches 86 must have an opposite polarity therefrom, in order to insure the desired operation of the device. On the other hand, the switches 101 and 102 must be inoperative under adverse track conditions, which result is simply accomplished by having the polarities of the lower poles of their magnets the same as those of magnets 46 and 87 respectively, so that the polarity of the pole 112, which is obviously the opposite of that of pole 111, may positively prevent the operation of the switches as the pole 112 passes thereunder, by respectively neutralizing and strengthening the polarities of the magnets 104 and 103.

When the track magnet 47 is in its normally raised, or favorable position, as shown in full lines in Figure 5, the pole 112 thereof will be laterally displaced from both sets of switches, and therefore cannot sufficiently influence them to cause their actuation. The pole 111, however, will now be in position to effect the operation of the switches 101 and 102, and since the polarity relations will be the same as when the pole 111 was in position to cooperate with the switches 39 and 86 for their actuation, corresponding operative effects will be obtained. It will now be noted that in the latter instance, the spacing of adjacent switches 101 and 102 will be made such as to allow the operation of the train at any speed up to the allowable maximum, thus providing what might be termed a full-speed control in contradistinction to the caution-speed control afforded through the switches 39 and 86.

By providing more than one of each of the switches 39 and 101 operation of the device is assured, it being evident that the proper operation of any one of these switches will short out the circuit 37 and thereby cause the setting of the brakes. Switches 86 or 102 should be positioned both ahead of and behind the switches 39 and 101 respectively to allow reverse operation of the train on a track arranged for two-way control, since one of the former must operate ahead of the latter with which it is associated in order to prevent setting of the brakes.

It will now be evident that a mechanism has been provided which will not only cause the setting of the brakes when a track section not in normal condition is reached by the train but will also cause the setting of the brakes when an excessive speed is reached even if the track section is in normal condition.

I claim:

1. In an automatic train control, the combination with a series of insulated track sections and an air-brake-system carried by the

train, a permanently magnetized track magnet associated with each of said sections, electro-magnetically operating means carried on the train adapted to be actuated by 5 said track magnet to effect an application of the air brakes when a section preceding the train is not in normal condition, and electro-magnetically operated means carried by said train and adapted to be actuated by said 10 magnet to prevent the application of said brakes by said first means when the train in approaching said section is travelling below a predetermined rate of speed.

2. In an automatic train control, the combination with a series of insulated track 15 sections and an air-brake-system carried on the train, a permanently magnetized displaceably mounted track magnet associated with each of said sections, means on said 20 train adapted to be actuated by said track magnet for effecting an application of said brakes when a track section preceding the train is not in normal condition, and means adapted to be actuated by said track magnet 25 to prevent the application of said brakes by said first means when the train is approaching said section below a certain rate of speed.

3. In an automatic control for trains, the combination with a series of insulated track 30 sections and an air brake system carried by the train, of a displaceable track magnet associated with each track section, means operative to displace a track magnet when 35 the associated track section is not in normal condition, means carried on the train operative to effect the application of the air brakes by and only when the train passes a displaced track magnet, and means carried 40 on the train operative by said displaced magnet to prevent the application of said brakes by said preceding means providing the speed of the train is below a certain rate.

4. In an automatic train control, the combination with a brake-system and a series 45 of insulated track sections, a magnet associated with each section, electromagnetically operated brake controlling means comprising an electric circuit, a magnetic switch in 50 said circuit adapted to be actuated by a magnet, and a second switch, and an electric circuit in which said second switch is contained adapted to magnetically influence said first switch and thereby prevent the actuation thereof by a track magnet.

5. An apparatus in accordance with claim 4 characterized by the second switch being positioned for actuation by a track magnet.

6. In an automatic train control, the combination with a series of insulated track 60 sections and an air-brake-system carried on the train, a track magnet associated with each of said sections, means on said train adapted to be actuated by a track magnet for effecting an application of said brakes when a

track section preceding the train is in adverse condition, means adapted to be actuated by a track magnet to prevent the application of said brakes by said first means when the train is approaching said section 70 below a predetermined minimum rate of speed, and means operative to cause an application of the brakes under said latter condition in case said last means fails to allow the application of the brakes by said 75 first means after preventing said application for a certain interval.

7. In an automatic train control, the combination with a brake-system and a series of insulated track sections, a track magnet 80 movable to assume different positions when the track is in normal and adverse conditions, means operative by said track magnet to cause the actuation of the brakes when the track is in adverse condition, means operative by said track magnet to cause the actuation of the brakes when a predetermined speed is exceeded by the train regardless of the condition of the track, and means operative by said track 85 magnet regardless of the condition of the track to render inoperative said brake actuation means when the train is travelling below a predetermined speed.

8. In an automatic train brake control, the combination with an air brake valve and a series of insulated track sections, a track magnet 90 movable transversely of a track section to assume different positions when the track is in normal and adverse conditions, means operative by said track magnet to cause the actuation of the air brake valve to set the brakes when said track is not in normal condition, means operative by said track magnet to cause the actuation of the air brake valve to set the brakes when a predetermined speed is exceeded, regardless 95 of the condition of the track, and means operative by said track magnet to render inoperative said air brake actuation means when the train is travelling below a predetermined speed.

9. In an automatic train brake control, the combination with an air brake and a series of insulated track sections, a track magnet 100 movable transversely of a track section to assume different positions when the track is in normal and adverse conditions, and means operative by said magnet to cause the application of the brakes when a predetermined speed is exceeded by the train when said magnet is in either of said 105 positions.

10. In an automatic train control, the combination with an air brake and a series 110 of insulated track sections, a track magnet movable to assume different positions when the track is in normal and adverse conditions, and means operative by said magnet to cause the application of the brakes when a 115

a predetermined maximum speed is exceeded by the train with the track in normal condition.

11. In an automatic train control, the combination with a brake system, track magnets, means carried on the train adapted to be actuated by said magnets to effect an application of the train brakes either when the track is clear or in adverse condition, and means carried on the train adapted to be actuated by said magnets to prevent the application of the brakes by said first means providing that when the track is clear the train is travelling under a predetermined maximum speed, or if the track is in adverse condition, the train is travelling under a predetermined minimum speed.

12. In an automatic train control, the combination with a brake system and a series of insulated track sections, magnets arranged in said sections, electro-magnetically operated means carried on the train adapted to be actuated by said magnets to effect an application of the train brakes when the track is not clear, electro-magnetically operating means carried by the train adapted to prevent the actuation of the brakes by said means providing the train is travelling below a predetermined minimum speed, electro-magnetically operating means carried by the train and adapted to be actuated by said magnets for causing an application of the brakes regardless of track conditions, and electro-magnetically operating means carried by the train adapted to be actuated by said magnets to prevent the application of the brakes by said last means providing the speed of the train is below a predetermined maximum value.

13. In an automatic train control, the combination with a brake system and a series of insulated track sections, a track magnet associated with each section adapted to lie in different positions when the associated section is in normal and adverse conditions, electro-magnetically operated means carried on the train adapted to be actuated by one of said track magnets to effect an

application of the brakes when the magnet is in the position occasioned by adverse track conditions, electro-magnetically operated means carried on the train arranged to be actuated by said magnet to prevent the application of the brakes by said first means providing the speed of the train is below a predetermined minimum value, electro-magnetically operated means carried on the train adapted to be actuated by said magnet to effect an application of the brakes when the magnet is in the position occasioned by normal track conditions, and electro-magnetically operated means carried on the train adapted to be actuated by said last mentioned means providing the speed of the train is below a predetermined maximum value.

14. In an automatic train control, the combination with a brake-system, track magnets, electro-magnetically operated brake controlling means comprising an electric circuit, normally inoperative means adapted to be actuated by a track magnet to short-circuit said circuit, a switch, and an electric circuit in which said switch is contained adapted to influence said means to prevent the actuation thereof by a track magnet.

15. In an automatic train control, the combination with a brake-system carried on the train, track magnets, means on said train adapted to be actuated by a track magnet for effecting an application of said brakes, means adapted to be actuated by a track magnet to prevent the application of said brakes by said first means when the train is approaching said section below a predetermined maximum rate of speed, and means operative to cause an application of the brakes under said latter condition in case said last means fails to allow the application of the brakes by said first means after preventing said application for a certain interval.

In testimony whereof, I have hereunto set my hand at Oakland, California, this 16th day of April, 1924.

THOMAS M. RIGGLE.
